HOT AIR FURNACE

Theodore R. Brien, Cherry Valley, N. Y.

Application October 7, 1932, Serial No. 636,715

2 Claims. (Cl. 126—99)

With the ordinary vertical furnace there is a comparatively short travel for the hot gases with the result that the furnace has to be operated at a high temperature and the gases enter the

5 chimney at a relatively high temperature which, of course, means inefficient operation.

In the hot air furnace embodying my invention there is a comparatively long fire travel and a sufficient amount of heat is transferred from 10 the flues to the air so that the waste gases leave the furnace at a relatively low temperature and the furnace may also be operated at a correspondingly low temperature.

My invention will best be understood by reference to the accompanying drawings in which I have illustrated a preferred embodiment thereof and in which

Fig. 1 is a front elevation, partially broken away, of a furnace embodying my invention;

20 Fig. 2 is a section taken along the line 2—2 of Fig. 1;

Fig. 3 is a perspective view of the flues;

Fig. 4 is a fragmentary plan view of the branched outlet flue leading from the combustion chamber;

25 Fig. 5 is an end view of Fig. 4;

Fig. 6 is a perspective view illustrating the end of a flue section which is provided with an access opening;

30 Fig. 7 is a longitudinal sectional view through Fig. 6 and illustrating a cover plate secured in position on the end of the flue;

Fig. 8 is a rear elevation of the cover plate;

35 Fig. 9 is an end elevation of the flue illustrated in Fig. 6; and

Fig. 10 is a sectional view illustrating a flexible joint between two adjacent sections of the flue.

Like reference characters indicate like parts 40 throughout the drawings.

Referring to the drawings, 10 indicates the front wall of a furnace, 11 the rear wall and 12 the top and side walls, the walls preferably comprising spaced plates for heat insulating purposes, a plate 13 extending across the bottom of the furnace. The walls forming the upper portion of the furnace are preferably arch-shaped as at 121, as indicated in Fig. 1.

45 A combustion chamber 14 is formed by walls 15 which are preferably cylindrical in cross section and flared upwardly as indicated in Fig. 2.

In the embodiment illustrated the walls are formed of sections 151, 152, 153 and 154, the lower edge of a given section interfitting with 50 a concave recess 16 formed in the upper edge

of the adjacent section, suitable incombustible packing material, such as rope asbestos 17, being interposed between the two to form a tight joint.

In the embodiment illustrated, I have shown 60 an oil burner 18 through which oil with a suitable amount of combustible air is introduced into the lower portion of the combustion chamber 14. It is to be understood, however, that my invention is not limited to the use of fluid fuel as the burning of gas, coal, powdered fuel or any other kind of fuel ordinarily used in heating apparatus is contemplated. In case solid fuel is to be used, then a grate would be interposed between the sections 151 and 152 and the fuel would be introduced through a front door 19 communicating with the upper portion of the combustion chamber.

The upper section 154 enclosing the combustion chamber is provided with a passage 20 with 70 which communicates an outlet flue 21 which is provided with three passages, the middle one of which, 211, communicates with a stack 22 and is provided with a damper 38 operated by a handle 39. The other two branches 212 gradually descend, as best shown in Fig. 3, and communicate 75 with flues 23 arranged in the upper portion and at the opposite sides of a heating chamber 24. The lower ends of the branches 212 are provided with flanges 25. Curved pipe sections 26 provided with flanges 27 complementary to the flanges 25 are interposed between the ends of the branches 212 and the main flues 23.

The flues 23 on opposite sides of the heating chamber are preferably of the same construction 90 and a description of one, therefore, will suffice for both. Each of flues 23 preferably comprises a comparatively long section 231 which is generally U-shaped in form and joined at one end by a comparatively short U-shaped section 232 to one leg of the adjacent long section. The complementary flanges for two sections 231 and 232 of the flue, which may be of the same character as the flanges 25 and 27 are illustrated in Fig.

10, the one flange 234 being provided with an annular recess 235 whereas the complementary flange is provided with a bead or slightly raised lug 236, registering with the recess 231, suitable incombustible packing material, preferably in the form of asbestos rope 237, being located in the recess so that, due to the pressure of the bead 100 against the packing, a gas tight joint is provided. When the raised lug portion 236 of one flange 234 of the flues engages the rope asbestos 105 which is interposed between the raised portion 110

and the recess 235 of the other flanges, the two flanges are slightly spaced, as illustrated, when the flanges are secured together by the bolts or rivets. This provides a flexible connection between the sections 231 and 232 as well as between the remaining sections of the flue.

A common outlet flue 28 is provided with two branches 281 which communicate with the uppermost branches 233 of the main flue 23, the other end being connected to the stack 22.

The front ends of the sections 231 are provided with access openings 29, preferably elliptical in form, as best shown in Figs. 6 and 7 and extend through openings in the front furnace wall. The access openings may conveniently be closed by means of cover plates 31 formed with flanges 32 surrounding the ends of the section 231. The cover plates are preferably equipped with a clamping bar 33 mounted on an operating stub shaft 34 passing through an opening in the cover plate 31 and provided at its outer end with an operating handle 35. The ends of the bar 33 engage cam grooves 36 formed on the inner surface of the end of the flue 231, as best shown in Figs. 6 and 7.

In assembling the cover plate, the bar is, of course, placed in position with the member 33 in vertical position as shown in Fig. 8. Then by turning the bar 33 it engages the cam grooves 36 and clamps the cover plate against the end of the flue section 231. Suitable packing material 37 is preferably interposed between the cover plate and the end of the flue.

Air is admitted to the lower portion of the heating chamber 24 through an air inlet opening 40 located at the bottom of the furnace, the air passing upwardly in contact with the walls of the combustion chamber 14 and over the flues 23 to one or more air outlet openings 41 which, of course, may lead to rooms which are to be heated.

In operation the heated gases are conducted from the upper portion of the combustion chamber 14 through the passage 20. When the furnace is initially started, the damper 38 is opened thereby permitting the gases to pass to the stack direct until the gases therein are sufficiently heated to create a draft. The damper 38 is then closed, and the heated gases gradually descend from the outlet flue 21 through the branches 212 and the sections 26 to the flues 23 located on opposite sides of the heating chamber. The gases then gradually ascend through the sections 231 and 232 and through the upper legs 233 to the outlet flue 28 through which they pass to the stack.

By providing branched flues on opposite sides of the heating chamber in the manner described and causing the gases to ascend in the major portion of the flues, I have provided a comparatively long travel for the hot gases and thereby obtained a high heat transfer from the hot gases to the air while providing a strong draft for the furnace.

The provision of the spaced flanges with interposed packing material is particularly important where there is a considerable drop in the temperature of the gases as in the described construction which would cause differences in expansion and contraction between different portions of the flue. Such differences are readily compensated for by the yielding packing.

The flues may readily be cleaned through the cleaning openings 29 of the sections 231 of the flue by removing the cover plates 31.

While I have described my invention in its preferred embodiments it is to be understood that the words which I have used are words of description rather than of limitation and that changes within the purview of the appended claims may be made without departing from the true scope and spirit of my invention in its broader aspects.

What I claim is:

1. In a hot air furnace, means defining a combustion chamber, means defining a heating chamber surrounding the combustion chamber, an outlet flue extending from the top of the combustion chamber to the rear of the heating chamber, and heating flues extending from opposite sides of the outlet flue and each having sections extending outwardly and downwardly and having parallel sections alternately connected at opposite ends and joined to a common outlet at the top of the heating chamber at the highest point of the flues and forming an arch over the sides and top of the combustion chamber, whereby the gases pass from the combustion chamber downwardly and outwardly and then upwardly around the sides of the combustion chamber and then inwardly toward the center and over the top of the combustion chamber, all of said flue branch connections having a gradually curved contour.

2. In a hot air furnace, means defining a combustion chamber, means defining an arch shaped air heating chamber surrounding the combustion chamber and having parallel front and back walls, heating flues in the form of an arch corresponding with the contour of the air chamber and positioned on opposite sides of the combustion chamber comprising long U-shaped sections having oval apertures at the closed end extending through the front wall, curved and downwardly extending sections joining the lower ends of the flues with the top of the combustion chamber, short U-shaped sections joining adjacent ends of the long U-shaped sections and a Y-shaped section joining the upper ends of the flues and forming a common outlet whereby the gases from the combustion chamber are first directed downwardly and outwardly and then upwardly and inwardly and are discharged at the highest point of the flue, all of said sections being detachably joined, and covers for closing the oval apertures of the closed end of the long U-shaped sections extending through the front wall.

THEODORE R. BRIEN.
